UNITED STATES PATENT OFFICE.

CHARLES A. LUNDGREN, OF DAYTON, OHIO, ASSIGNOR, BY MESNE ASSIGNMENTS, TO THE NATIONAL CASH REGISTER COMPANY, OF DAYTON, OHIO, A CORPORATION OF OHIO, (INCORPORATED IN 1906.)

CASH-REGISTER.

998,623.

Specification of Letters Patent. Patented July 25, 1911.

Application filed March 10, 1906. Serial No. 305,316.

To all whom it may concern:

Be it known that I, CHARLES A. LUNDGREN, a citizen of the United States, residing at Dayton, in the county of Montgomery and State of Ohio, have invented certain new and useful Improvements in Cash-Registers, of which I declare the following to be a full, clear, and exact description.

This invention relates to cash registers and has for its object to provide a machine especially for use in canceling so called bundle tickets or delivery slips.

In many commercial houses, for example, a sale slip is made out in duplicate, one copy being filed and the other copy being given to the customer who thereupon takes the purchase away with him or her. This system in practice is fairly satisfactory in cases where the customer does not desire the bundle delivered by the store but in cases where a delivery is to be made as by wagon, opportunity is given to the clerks to defraud the proprietor. This duplicate slip system is also used in connection with a well known type of cash register in which the machine prints the amount of the sale in two places on a slip which is then severed into two parts, one of which is retained in the machine as a voucher, the other being ejected and serving as a receipt. In the use of such machines in connection with a sale for immediate delivery the amount received must be added in on the machine in order to print on the slip, without which the bundle will not be wrapped. In the case of a sale with future delivery an operation of the machine is made and the sale slip attached to the bundle which is then taken to a room to be wrapped, and in such cases some means of authorizing the wrapping and sending out of the package must be provided.

My invention aims to provide means for authorizing such wrapping and delivery and to this end I employ a delivery slip or bundle ticket longer than the usual sale slip, which is adapted to have printed thereon such matter as the word "Paid" and the date or other desired matter. The portion of the slip bearing this matter may be detached and pasted or otherwise attached to the bundle, and will be understood as authorizing its delivery.

In particular this invention aims to im-

prove the machine shown in application bearing Serial Number 160,416, filed June 6, 1903, by Thomas Carroll. The machine shown in said application is designed to make two printing impressions on a sale slip, one part of the slip being retained in the machine after the impression is made and the other part being taken from the machine after printing.

For use in connection with future delivery sales I provide a longer bundle ticket or delivery slip than the usual sale slip and means are provided for marking this slip with a record of any desired matter *e. g.* the word "Paid" and the date. The machine includes an extra printing device so located as not to operate on the usual sale slip as such slip is not long enough to reach the extra printing device but when a longer bundle ticket is inserted in the machine the above stated additional impression will be made.

With these and incidental objects in view, the invention consists in certain novel features of construction and combinations of parts, the essential elements of which are set forth in appended claims and a preferred form of embodiment of which is hereinafter specifically described with reference to the drawings which accompany and form part of this specification.

Of said drawings: Figure 1 represents a vertical transverse section through the machine and cabinet showing the operating cam and the main printing table. Fig. 2 represents a vertical transverse section through the machine and cabinet showing the vertical shaft and its operating mechanism. Figs. 2^a, 2^b and 2^c are detail views of the auxiliary printing device and Fig. 3 represents a rear view of part of the machine with the cabinet partly broken away.

The main revolution shaft 10 is rotated by any suitable driving mechanism and receives one complete revolution at each operation of the machine in the direction of the arrow in Fig. 1.

Fast to the shaft 10 is a disk 11 in which is formed a cam groove 12 adapted to engage an anti-friction roller 13 mounted on a reciprocating lever 14. The lever 14 is so formed as to straddle the shaft 10 and has an upward and rearwardly extending arm

15. Extending laterally from the arm 15 is a rack 16 which engages a pinion 17 mounted on a vertical shaft 18 which is given a partial revolution at each operation of the 5 machine as will be explained later on. The other end of the lever 14 is pivoted to an arm 19 which is in turn pivoted to the framework of the machine.

As seen in Fig. 3 the hub of the pinion 17 10 is provided with a pin 20 which extends into a groove 21 in the shaft 18. This makes it possible for the shaft to receive a reciprocatory movement in addition to and without interfering with its revolute movement.

15 This reciprocatory movement is produced by the following mechanism: Fast to the shaft 10 is a disk 25 in which is formed a cam groove 26 adapted to operate upon an anti-friction roller 27 mounted on an arm 20 extending upwardly from a lever 28. The lever 28 is pivoted on the frame work of the machine at 29 and has at its other end a pin

30 adapted to engage between two disks 31 fast to the lower end of the shaft 18. The 25 above mentioned disks 11 and 25 and others of the same kind will hereafter be mentioned as box cams. The relative timing of these two movements of the shaft 18 will be described later on.

30 Removably secured to the upper end of the shaft 18 is a frame 35 which contains the auxiliary printing wheels 36. These printing wheels 36 have suitable numbers and characters for printing the date equally

35 distributed around their periphery and are held in printing alinement by suitable spring pressed alining plungers 37 engaging toothed alining wheels 38 of which there is one fastened to each printing wheel.

40 The hub 39 of the frame 35 is held in position against a collar 40 (which is secured to the shaft 18) by a thumb screw 41 and is prevented from turning on said shaft by a tongue and groove 42 between said hub 39

45 and the collar 40. In the forward end of the frame 35 is mounted a spring pressed plunger 43 which has a flange 44 at its upper end to limit its movement in one direction. In the normal position of the frame 35 (see

50 Fig. 2) the plunger 43 rests on the cabinet of the machine with its spring contracted but as soon as the frame 35 is raised the plunger will assume a position like that shown in Fig. 3. Fastened to the under side

55 of the frame 35 is a plate 45 having the word "Paid" engraved thereon so as to print said word in connection with the date. In a recess in the cabinet there is an inking pad 46 upon which the auxiliary printing wheels 36 and plate 45 rest when the frame 35 is in normal position. This supplies the wheels and plate with ink.

60 The impression platen 50 is pivoted at 51 to the framework of the machine and has an 65 impression block 52 made of rubber or other

suitable material. A spring 55 normally tends to draw the platen down but is normally prevented from doing so, (see Fig. 3) by a spring pressed pawl 53 which engages a laterally projecting pin 54 mounted 70 on the platen 50. This pawl 53 is pivoted at 56 and has a foot 57 which is operated upon by a downwardly projecting foot 58 of a tripping pawl 59 to trip the pawl 53 from the pin 54. This will allow the platen 50 to 75 be drawn downwardly by the spring 55 and will prevent any printing as the impression block 52 will then be below the printing line. The pawl 59 is provided with a pin 60 which contacts with the framework of the 80 machine to limit its downward movement. A spring 61 is coiled around the hub of the pawl 53 and tends to force said pawl into locking engagement with the pin 54 of the impression platen 50. The pawl 59 is operated upon by the plunger 43 in the following manner.

If a delivery slip (which is longer than the regular sale slip) is inserted into the 90 machine it will extend over the impression block 52 and also over a hole 62 in the cabinet of the machine. When the machine is operated the shaft 18 will first be lifted to raise the auxiliary printing mechanism from the inking pad 46. The shaft 18 will now be 95 rotated to bring said printing mechanism into the position shown in Fig. 3 and will then be lowered to print on the delivery slip. The slip being in position will receive the printed impression because the paper over the hole 62 prevents the plunger 43 from entering said hole and operating the pawl 59 to trip the pawl 53 from engagement with the pin 54. After the printing is done the shaft 18 is again raised and then rotated 100 back to normal position, the last movement being to lower the auxiliary printing mechanism so the type wheels 36 and the plate 37 will rest on the inking pad 46. The spring 105 of the plunger 43 is light enough to allow the plunger 43 to operate without breaking through the paper.

If there is only a regular sale slip in the 110 machine the following will result: The sale slip is not long enough to extend over the impression block 52 and the hole 62 therefore the plunger 43 will (upon the operation of the machine) operate the pawl 59 to trip the pawl 53 from engagement with the pin 54 thereby allowing the impression platen 50 to be drawn downward by its spring 55 until the pin 54 strikes the framework of the machine. It will be readily understood that in this position the auxiliary 120 printing will be rendered ineffective.

The impression platen 50 is restored to its 125 normal position by the following mechanism. Mounted loosely on a shaft 70 is a pawl 71 having a downwardly extending arm 72 and an upwardly extending shoulder 130

73. A stop pin 74 limits the movement of the pawl 71 in one direction. A suitable spring (not shown) normally tends to draw the pawl 71 against the pin 74. Mounted on the box cam 80 are two pins 76 and 77 which strike the forward side of the arm 72 of the pawl 71 to lift the shoulder 73 upward against the under side of the impression lever 50 to restore the same to normal position. The pin 76 first acts on the arm 72 to restore the platen 50 if it has been accidentally or otherwise tripped and the pin 77 acts on said arm to restore said platen after the printing operation is completed. 15 The main printing wheels 90 are set to print the different amounts by mechanism described and shown in the above mentioned pending application. The main printing platen or table 91 has a downwardly extending arm 92 provided with an anti-friction roller 93 which is operated upon by a cam groove 94 of the box cam 80 to vibrate the table 91 up and down twice to make two impressions on the paper strip. Between these 20 two impressions the paper slip is fed forward by the following mechanism. A cam groove 95 is formed in the box cam 25 and acts upon an anti-friction roller 96 mounted upon one end of a bell crank lever 97 30 pivoted on a stub shaft 98 to reciprocate a rack bar 99 which meshes with a pinion 100 mounted upon one end of a shaft 101. The shaft 101 is mounted in the table 91 and has mounted thereon a feed roller 102. A pressure roller 103 mounted on a lever 104 is so arranged as to come into contact with the feed rollers at the proper time. The above mentioned main printing mechanism and feeding mechanism is fully described and 40 shown in the above mentioned pending application to which reference may be had for a more detailed description. The operation of the machine and the relative timing of the different mechanisms will now be described. 45

Let us suppose that the main printing wheels 90 have already been set to their printing position and that a delivery slip has been inserted to extend over the main printing table 91 and also over the impression block and the hole 62. The main shaft 10 will rotate in the direction of the arrow (see Fig. 1) and the following will result. First the arm 28 will raise the shaft 18 so as to lift the auxiliary printing mechanism free from the inking pad 46. During this raising of the shaft 18 the main printing table 91 has also been raised to print the amount previously set up by the machine. About 55 the same time that this printing is done the pin 76 will strike the arm 72 of the pawl 71 and will restore the impression platen 50 if it had been accidentally or otherwise tripped before the machine had been started. Immediately after the shaft 18 is raised the

arm 14 will vibrate to revolve the shaft 18 and bring the auxiliary printing mechanism into a position as shown in Fig. 3. Next the main printing table 91 will be lowered slightly and the paper delivery slip will be fed forward by the feed roller 102. After this feeding forward of the slip takes place the main printing table 91 is again raised to print the amount on the slip a second time after which the table 91 is lowered to its normal position. While the table 91 is being raised to print the second time the shaft 18 is lowered by the arm 28 to bring the auxiliary printing mechanism against the slip to print the word "Paid" and the date. It will be clearly seen that if there is no paper over the hole 62 that the platen 50 will be released as previously explained. The shaft is now raised again and rotated back to its normal position after which the pin 77 will strike the arm 72 of the pawl 71 and raise the shoulder 73 to restore the impression platen 50 to its normal position. At the very last part of the revolution of the shaft 10 the shaft 18 is lowered to bring the auxiliary printing mechanism against the inking pad 46. 75 80 85 90 95

While the form of mechanism here shown and described is admirably adapted to fulfil the objects primarily stated, it is to be understood that it is not intended to confine the invention to the one form of embodiment herein disclosed, for it is susceptible of embodiment in various forms all coming within the scope of the claims which follow. 100

What is claimed is as follows:

1. In a cash register, the combination with a movable platen normally held stationary in printing line, a printing element movable toward and away from said platen, means for giving the printing element a constant excursion, and means controlled by the article to be marked for permitting a movement of said platen away from the printing line, to prevent a printing impression. 105

2. In a cash register, the combination with a printing device, of a platen relatively movable and means allowing conjoint movement of the device and platen when no impression is to be taken. 110

3. In a cash register, the combination with a platen, of means to hold it normally in condition to be operated against, and means for tripping said holding means when no impression is to be taken. 115

4. In a cash register, the combination with a set of printing wheels, of an ink pad against which said wheels normally rest, a platen, a shaft supporting said wheels, and means for rotating and axially sliding the shaft. 120 125

5. In a cash register, the combination with a printing wheel, of a frame supporting said wheel, a plunger also supported by said frame, a platen, means normally holding 130

the platen in position to be operated against, and means operated by the plunger for tripping said holding means.

6. In a cash register, the combination with 5 a platen, of means to hold it normally in condition to be operated against, means for tripping said holding means when no impression is to be taken, and means for resetting said holding means.

10 7. In a cash register, the combination with a printing wheel, of a frame supporting said wheel, a plunger also supported by said frame, a platen, means normally holding the platen in position to be operated against, 15 means operated by the plunger for tripping said holding means, and means for resetting said holding means.

8. In a cash register, the combination with 20 a printing device and a platen conjointly movable, of means permitting relative movement of the device and platen when an impression is to be taken and permitting conjoint movement of the device and platen when an impression is not to be taken.

25 9. In a cash register, the combination with a printing device of a shaft supporting same, an operating shaft, and means on said operating shaft to both rotate and axially reciprocate said supporting shaft.

30 10. In a cash register, the combination with a movable platen normally held stationary in printing line, a printing element movable toward and away from said platen, means for giving the printing element a constant excursion of movement, means movable with the printing element and under control of the article to be marked for permitting a movement of said platen away

35 from the printing line.

40 11. In a cash register, the combination with a printing device comprising a set of printing wheels, of a supporting shaft therefor, a gear splined on said shaft for causing

rotation thereof, a disk on said shaft a lever engaging said disk, and a box cam controlling said lever to shift said shaft axially. 45

12. In a cash register, the combination with a frame, of a plurality of printing wheels and a plunger supported by said frame, a pivoted platen, means normally 50 supporting said platen in position to be operated against, and means operated by said plunger tending to trip said platen supporting means at each operation of the machine.

13. In a cash register, means for stamping 55 tickets, comprising a set of printing wheels, a platen, a shaft supporting said wheels, a gear on said shaft for rotating same, to bring the printing wheels over the platen, a lever for reciprocating said shaft, to bring 60 the wheels and platen together, and a common means for operating said gear and lever.

14. In a cash register, the combination with a platen, of means normally supporting the same, means for tripping said supporting means, and means for restoring said platen and tripping means, comprising a lever, a box cam and two pins mounted on 65 said box cam, to operate said lever.

15. In a cash register, the combination with a main printing device, of an auxiliary printing device, both printing devices adapted to print on a paper slip of sufficient length to be engaged thereby, a platen for the auxiliary printing device, a means for moving the platen to an ineffective position when the cash register is operated in connection with a slip of insufficient length and thereby disabling the auxiliary printing device. 70 75 80

In testimony whereof I affix my signature in the presence of two witnesses.

CHARLES A. LUNDGREN.
